United States Patent Office

Des. 202,218
Patented Sept. 7, 1965

202,218

PAIR OF SUNGLASSES

Fabor A. Robison, 2600 Olive Ave., Burbank, Calif.

Original design application Jan. 20, 1964, Ser. No. 78,262.
Divided and this application Mar. 24, 1965, Ser. No.
84,422

Term of patent 14 years

(Cl. D57—1)

FIG. 1.

FIG. 2.

FIG. 3.

FIG. 1 is a perspective view of a pair of sunglasses embodying my new design,

FIG. 2 is a cross sectional view taken on the line 2—2 of FIG. 1, and

FIG. 3 is a cross sectional view taken on the line 3—3 of FIG. 1.

This application is a division of my copending application Serial No. D. 78,262, filed January 20, 1964.

I claim:

The ornamental design for a pair of sunglasses, substantially as shown and described.
